ADJUSTABLE SURGICAL FRAME FOR
HOSPITAL BEDSRoy L. Allaire and Charles W. Jeffries,
Stamford, Conn.

Application January 3, 1934, Serial No. 705,080

18 Claims. (Cl. 128—84)

This invention relates to new and useful improvements in adjustable surgical frames for hospital beds.

The invention comprehends an adjustable frame as stated which includes various bars and devices for properly supporting a patient and applying a pull to a broken arm or leg while the latter knits. In fact, it is the main aim or object of the invention to provide a frame which is readily adjusted into the desired positions and which includes means readily available and easily adjusted or operated by a doctor or nurse to take care of a patient having any broken bones, different parts of the frame being particularly adapted for different purposes but the various parts of the frame providing as far as possible every means necessary for taking care of a patient irrespective of what bone or bones are broken.

Other objects and advantages will become apparent from a consideration of the following detailed description taken in connection with the accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:

Fig. 1 is a side elevational view showing the improved frame in place on a bed;

Fig. 2 is a somewhat similar view but showing the frame in association with a stretcher or support and as used to raise and shift the stretcher or support;

Fig. 3 is a top plan view of the bed and frame as shown in Fig. 1;

Fig. 4 is a sectional view taken substantially along the line 4—4 of Fig. 3;

Fig. 5 is a sectional view taken substantially along the plane of the line 5—5 of Fig. 1 and showing various adjusted positions of a foot bar employed;

Fig. 6 is a detail elevational view showing the windlass of Fig. 2;

Fig. 7 is an end view of the stretcher of Fig. 2; and

Fig. 8 is a detail sectional view showing the connection between a lifting bow and the side rods of the stretcher;

Fig. 9 is a detail view illustrating a clamp employed; and

Fig. 10 is a sectional view showing a swivel joint used.

Referring in detail to the drawings at 10 is

generally indicated a bed including a head 11, a foot 12, side rails 13 and a mattress or the like 14. A pair of uprights 15 each at its upper end carrying a T fitting 16 are secured one to each of the head corner posts of the bed as by clamps 17 and it is noted that the uprights 15 as here shown are in the form of lengths of pipe or tubing although they are not necessarily restricted to being made of such material. Preferably, the uprights 15 extend a substantial distance above the head 10 of the bed and a cross bar 18 extends through and is supported by the T fittings 16 and may be held in place in them by thumb screws 16a or the like.

A second pair of uprights 19, each at its upper end carrying a T fitting 20, are provided and the uprights 19 are each secured to one corner post of the foot of the bed as by a pair of the clamps 17 and such uprights extend a substantial distance above the foot of the bed. A cross bar 21 extends through the T fittings 20 and is supported thereby and is slideable therethrough so as to project more or less as desired at a selected side of the bed and may be secured in adjusted position by thumb screws 20a threaded through the 25 fittings.

The upper end portion of either or both of the uprights 15 may be screw threaded as at 22 and mounted on this portion of each upright is a T fitting 23, slidably adjustable vertically thereon 30 and held in adjusted position by nuts 23a threaded on said portion 22. An arm 24 is, in each instance, threaded into this fitting 23 and such arms include sections 25 and 26 which sections are connected by a swivel 27. This swivel 35 may be of any desired construction but preferably includes portions 28 and 29 (see Fig. 10) secured to the respective arm sections 26 and 25 and connected by a vertical bolt or pin to which threads a thumb nut or means 30 whereby the sections 40 may be drawn tightly into engagement with one another. Obviously, on loosening the means 30 the arm sections 25 and 26 may be adjusted relatively about the bolt or pin of the swivel 27 as a pivot.

It will be noted that the free ends of the arms 24 are supported on the cross bar 21 at the foot of the bed and may be secured thereto by hooks 81 passed through a selected opening 80 in the sections 26 and having nuts 82 on their upper ends. Attention is directed to the fact that the arms 24 connected with the respective uprights 15 are of exactly the same construction and they are preferably each adjustably connected with their respective uprights. Owing to the swivel 55

joint 27 the arms 24 may be readily adjusted into a variety of positions. For example, the arm 24 at the lower side of Fig. 3 is adjusted substantially to its outermost position as shown in full lines but in the broken lines it is shown in substantially its innermost position. That is, it may be adjusted into any position between its position A and its position B. The arm at the far side of the bed in Fig. 3 in its full line position C is in position corresponding with the broken line position B of the other arm. However, this second arm may be adjusted into any desired position, as, for example, the broken line position D. Of course, to permit of adjustment of the arms the nuts 82 must be loosened and after the desired adjustments have been made the nuts are tightened.

All of these various positions of adjustment are made possible due to the fact that the arms may be moved about the uprights 15 as pivots and due to the swivel joints in the arms. If desired, the arms may be crossed one above the other, and this is easily accomplished by adjusting the T fitting 23 of one arm downwardly or upwardly on its uprights so as to dispose it below or above the corresponding fitting of the other arm. Since relative movement of the arms due to the swivel connection 27 is about a vertical pin or axis it will be appreciated the arms are only adjustable, insofar as the swivel is concerned, in a horizontal plane. The cross bar 21 may be adjusted into an extreme position extending beyond one side or the other of the bed so as to support an arm 24 in any desired position of angular adjustment.

A side outlet T fitting 31 is slideable on the cross bar 18 and extending horizontally outwardly from and carried by such fitting is an arm 32 disposed over the bed. Also, connected with the fitting 31 and extending downwardly vertically therefrom is an arm 33 detachably secured to the bed as by a clip 34. The arm 33 merely serves as a means for securing the fitting 31 against turning movement about the cross bar 18 and in the desired position along the bar and thereby serves to sustain the arm 32 in the desired position with respect to the longitudinal edges of the bed. This arm 32 carries a pulley 35 which may be secured in the desired position on the arm as by having its stem passed through a selected opening 36 in the arm and then secured in place as by a nut or the like 37. Of course, it will be understood that the pulley 35 may be secured in place by other means and any means may be used for securing the pulley if such means provides for adjustment of the pulley along the arm.

Extending laterally from one of the uprights 15 is a bracket 50 mounting a fitting 38 and this fitting is turnable about the said bracket and slidably adjustable vertically thereon and may be secured in position as by means of a pinch-bind including the screw 38a. An arm 41 is connected with the fitting 38 and the outer end of arm 41 is in turn connected with the arm 42 by means of one of the swivel connections 27. Slidable on the arm 42 is a fitting 43 from which extends a prop 44 comprising telescoping sections 45 and 46 of which the section 45 is split at its lower end and adapted to be drawn together on tightening of a bolt 47 whereby to grip the section 46 and rigidly secure the sections 45 and 46 in the desired position of adjustment or in the position of adjustment where they are of the required length. Of course, fitting 43 is turnable about the arm 42 as a pivot. The lower end of the prop section 46 is preferably U-shaped or bifurcated

as at 48 (see Fig. 4) and it is adapted to receive or straddle a bed side rail 13 and be secured in position as by a clamping bolt or means 49.

Adjustable along the arm 42 is a pulley 51 and while the pulley may be secured as in the case of the pulley 35 on the arm 32, pulley 51 is shown as supported by a clamp 52 which embraces the arm 42 and may secure the pulley in any desired position of adjustment on the arm. It will now be understood that owing to the fit of the fitting 38 on the bracket 50 and to the adjustability of the prop 44 the arms 41 and 42 may be adjusted vertically with respect to the bed and further owing to the swivel joint 27 connecting said arms and to the fit of the fitting 38 on the bracket 50 the said arms may be swung into practically any position of horizontal adjustment with respect to the bed so as to dispose the pulley 51 at the desired elevation and in the desired spaced relation and in the desired angular relation to the bed. When the arms 41 and 42 are properly adjusted the clamping nut 30 of the swivel connection may be tightened as may also be the clamping screws 47 and 49 of the prop and prop connection with the side rail of the bed respectively. Since the prop may be adjusted along the side rail of the bed and along the arm 42 it will be apparent that the prop may be so positioned as to a maximum extent directly sustain any pull on the pulley 51.

A pair of similar brackets 53 and 54 are secured to the uprights 19 and each bracket includes a T fitting 58 adjustable vertically on its upright and which may be secured in the desired position of vertical adjustment by the insertion of the cross pin 56 in a selected one of the openings 57. Each bracket includes one of the swivel joints 27 and in its outer end each bracket includes a T fitting 58. From this it will be understood that the outer end portion of each bracket may be angularly disposed relative to its portion on the upright and that the parts or portions may be secured in such adjusted positions on tightening of the means 30 of the swivels. A cross bar 59 is received in the outer portions or T fittings 58 of the two brackets and is longitudinally adjustable through them.

This cross bar 59 may be equipped with the pulley 60 to be secured in the desired position along the bar as by a clamp not shown but similar to the clamp 52 securing the pulley 51 to the bar or arm 42. It will be understood that for different purposes the cross bar 59 will be adjusted into different positions and a flexible means as a rope or the like may be passed over the pulley 60 to connect a weight with a leg or the like to maintain a tension on the bone thereof while the latter knits. Further, any desired number of pulleys may be secured to this cross bar. In place of the bar 59, a bar 62 having one end portion 60 bent to form a crank 63, may be mounted by the brackets 53 and 54. However, in place of a substitution a detachable crank might be provided with which to turn the cross bar 59 when a windlass is necessary as will later be set forth.

Fig. 5 shows some of the various adjustments obtainable due to the particular mounting of the cross bar 59 and in that figure it will be noted that in its dotted line position the bar is extending between the uprights 19 and with its right hand end portion inwardly of said uprights. In the full line position of Fig. 5 the bracket 53 is adjusted to dispose its T fitting 58 at the inner side of one of the uprights 19 and the bracket 54 is slightly inclined so as to bring its T fitting 58

into alignment with the corresponding fitting of the bracket 53. The cross bar 59 is arranged in position extending between the uprights 19 and adjusted to have its right hand end portion disposed laterally beyond the right side of the bed and at a considerable distance below the foot of the bed.

Figs. 2, 6 and 7 disclose the structure to be used when a patient has a broken back or the like and these figures disclose a stretcher 64 including a sheet or pad 65 which may have a bed pan opening 66 therein and the longitudinal edges of which are turned on themselves providing loops removably receiving rod or bars 67. A pair of lifting or supporting bows 68 are disclosed in spaced relation to one another and have their ends pass through the rods or bars 67 and such ends of the bows have threaded to them nuts 69 whereby the bows are removably connected with the rods or bars. Each bow may carry an eye 70. When the stretcher is to be used pulleys 71 are secured to a section 26 of one of the arms 24 as by clamps 72, such mounting providing for ease of adjustment of the pulleys along the arm section. Another or guide pulley 73 may be secured to an arm section in a like manner.

Cables 74 are run over the pulleys 71 and over pulleys 75 connected with the eyes 70 and these cables are then passed through the pulley 73 and secured to the shaft 62 of the windlass. Obviously, with this arrangement on turning of the crank 63 in one direction or another, the stretcher 64 will be raised or lowered. To maintain the stretcher in a raised position a pin 76 may be inserted through one of the T fittings 58 as the T fitting of the bracket 53 and through the bar portion 62 of the windlass.

When the humerus bone is broken a weight to keep the broken ends of the bone apart may be attached to a cable trained over the pulley 51 and secured at its inner end to the lower portion of the broken humerus. The arm may be supported by a sling or the like attached to a cable running over the pulley 35 carried by the arm 32 and to enable the patient to exercise his elbow and the bones of his hand and the like a similar weighted cable may be passed over a pulley (not shown) removably attached to one of the sections of one of the arms 24. Of course, the various parts may be adjusted, as above explained when considering the separate parts, so as to have the pull in each instance exerted in exactly the correct direction.

A broken leg may be supported in a sling in turn supported by weighted cables passed over pulleys 71 carried by a carriage 78 suspended on an arm section 26 by rollers 79. Obviously, owing to the connections of the arm with the upright 15 and owing to the swivel joint 27 and to the fact that the cross bar 21 may be longitudinally adjusted, the arm 24 mounting the carriage 78 may be shifted to the desired angle to properly support the broken leg. Additionally, a pull to maintain the broken ends of the bone separated may be exerted by a weight acting through a cable trained over the pulley 60. Whenever desired, a pulley 73 or other pulleys (not shown) may be secured to the sections 26 of the arms 24 either by having stems passed through openings in said arms or by means of clamps similar to the clamp 52 attaching a pulley 51 to the arm 42. It is only necessary that the pulleys be adjustable along the arm sections 26 and readily applicable to and removable from such arm sections.

When the stretcher 64 is being used one of the arms 24 may be swung as to the broken line position B of Fig. 3, and then connected with the stretcher as above stated after which the stretcher may be elevated off the bed as shown in Fig. 2. Thereafter, the arm may be swung to its position A to dispose the stretcher and the patient at the side of the bed and then the windlass may be operated to lower the stretcher and the patient onto another bed. By reversing the action the patient and stretcher may be deposited on the bed on which our adjustable frame is mounted. The stretcher is easily placed under the patient since the bars or rods 67 of the stretcher may be removed and the sheet or pad 65 disposed under the patient in the same manner as a clean bed sheet. Thereafter, the bars are inserted into the loops at the longitudinal edges of sheet 65 and the bows 68 attached to said rods.

From the foregoing it will be seen that our improved adjustable frame provides means for taking care of practically any broken bone case. All the parts may be easily adjusted into desired positions so as to support an arm, leg or the like at the proper angle and so as to have the pull exerted in the desired direction. Of course, if both arms are broken then two uprights 15, each equipped with one of the brackets 50, would be used and two sets of means including the arms 41 and 42 and prop 44 would be used, one set of means being located at each side of the bed. Also, any desired number of pulleys may be secured to the arms 24 and if desired a carriage 78 may be disposed on the section 26 of each arm 24.

Having thus set forth the nature of our invention, what we claim is:

1. In combination, a pair of uprights to be disposed at one end of a bed and an upright to be disposed at the other end of the bed, a cross bar supported on said pair of uprights and adjustable across the same to project more or less at a desired side of a bed, an arm connected at one end with the other upright for movement about the same as a pivot and for adjustment vertically thereon, a swivel connection in said arm, and said arm at its other end supported by said cross bar.

2. In combination, a pair of uprights to be disposed at one end of a bed and an upright to be disposed at the other end of the bed, a cross bar supported on said pair of uprights, an arm connected at one end with the other upright for movement about the same as a pivot, a swivel connection in said arm, and said arm at its other end supported by said cross bar.

3. In combination, a pair of uprights to be disposed at one end of a bed and an upright to be disposed at the other end of the bed, a cross bar supported on said pair of uprights, an arm connected at one end with the other upright for movement about the same as a pivot, a joint in said arm and including a vertical pivot whereby the arm portions have relative movement in a horizontal plane only, and said arm at its other end supported by said cross bar.

4. In combination, a pair of uprights to be disposed at one end of a bed and an upright to be disposed at the other end of the bed, a cross bar supported on said pair of uprights and adjustable across the same to project more or less at a desired side of a bed, an arm connected at one end with the other upright for movement about the same as a pivot, a joint in said arm

- and including a vertical pivot whereby the arm portions have relative movement in a horizontal plane only, and said arm at its other end supported by said cross bar.
5. In combination, a pair of uprights to be disposed at one end of a bed, a bracket on each of said uprights and vertically adjustable thereon, each of said brackets including an arm portion of which one has a swivel joint intermediate its ends, and a cross bar supported by the outer ends of said bracket arm portions.
10. In combination, a pair of uprights to be disposed at one end of a bed, a bracket on each of said uprights and vertically adjustable thereon, each of said brackets including an arm portion of which one has a swivel joint intermediate its ends, each of said bracket arm portions including a tubular portion at its outer end, and a cross arm supported in and adjustable longitudinally through said tubular portions.
15. In combination, a pair of uprights to be disposed at one end of a bed, a bracket on each of said uprights and vertically adjustable thereon, each of said brackets including an arm portion of which one has a swivel joint intermediate its ends, and a cross bar supported for longitudinal adjustment on the outer end portions of said bracket arm portions.
20. In combination, a pair of uprights to be disposed at one end of a bed, a bracket on each of said uprights and turnable relative thereto and vertically adjustable thereon, each of said brackets including an arm portion of which one has a swivel joint intermediate its ends, and a cross bar supported by the outer ends of said bracket arm portions.
25. In combination, a pair of uprights to be disposed at and extending above one end of a bed, a bracket on each of said uprights and turnable relative thereto and vertically adjustable thereon, each of said brackets including an arm portion of which one has a swivel joint intermediate its ends, and a cross bar supported for longitudinal adjustment on the outer end portions of said bracket arm portions.
30. In combination, a pair of uprights to be disposed at and extending above one end of a bed, a cross bar supported on the upper end portions of said uprights, a coupling adjustable along said cross bar, an arm secured to said coupling to extend over a bed, a pulley on said arm, a second arm secured to said coupling and extending substantially at right angles to said first arm, and means for detachably securing said second arm to a bed.
35. In combination, a pair of uprights to be disposed at one end of a bed, a bracket on each of said uprights and vertically adjustable thereon, each of said brackets including an arm portion of which one has a swivel joint intermediate its ends, and a cross bar supported by the outer ends of said bracket arm portions.
40. In combination, a pair of uprights to be disposed at and extending above one end of a bed, a cross bar supported on the upper end portions of said uprights, a coupling adjustable along said cross bar, an arm secured to said coupling to extend over a bed, a pulley on said arm, a second arm secured to said coupling and extending substantially at right angles to said first arm, and means for detachably securing said second arm to a bed.
45. In combination, a pair of uprights to be disposed at and extending above one end of a bed, a cross bar supported on the upper end portions of said uprights, a coupling adjustable along said cross bar, an arm secured to said coupling to extend over a bed, a pulley on said arm, a second arm secured to said coupling and extending substantially at right angles to said first arm, and means for detachably securing said second arm to a bed.
50. In combination, a pair of uprights to be disposed at and extending above one end of a bed, a cross bar supported on the upper end portions of said uprights, a coupling adjustable along said cross bar, an arm secured to said coupling to extend over a bed, a pulley on said arm, a second arm secured to said coupling and extending substantially at right angles to said first arm, and means for detachably securing said second arm to a bed.
55. In combination, a pair of uprights to be disposed at and extending above one end of a bed, a cross bar supported on the upper end portions of said uprights, a coupling adjustable along said cross bar, an arm secured to said coupling to extend over a bed, a pulley on said arm, a second arm secured to said coupling and extending substantially at right angles to said first arm, and means for detachably securing said second arm to a bed.
60. In combination, a pair of uprights to be disposed at and extending above one end of a bed, a cross bar supported on the upper end portions of said uprights, a coupling adjustable along said cross bar, an arm secured to said coupling to extend over a bed, a pulley on said arm, a second arm secured to said coupling and extending substantially at right angles to said first arm, and means for detachably securing said second arm to a bed.
65. In combination, a pair of uprights to be disposed at and extending above one end of a bed, a cross bar supported on the upper end portions of said uprights, a coupling adjustable along said cross bar, an arm secured to said coupling to extend over a bed, a pulley on said arm, a second arm secured to said coupling and extending substantially at right angles to said first arm, and means for detachably securing said second arm to a bed.
70. In combination, a pair of uprights to be disposed at one end of a bed, a bracket on each of said uprights, each of said brackets including a horizontal arm portion of which one has a swivel joint intermediate its ends, and a cross bar sup-

ported by the outer ends of said bracket arm portions.

18. In combination, a pair of uprights to be disposed at one end of a bed, a bracket on each of said uprights, each of said brackets including an arm portion of which one has a swivel joint in-

termediate its ends, a cross bar supported by the outer ends of said bracket arm portions, and said cross bar including a crank portion for turning the cross bar.

ROY L. ALLAIRE.
CHARLES W. JEFFRIES.
